(57) **CLAIM**

The ornamental design for a computer chassis, as shown and described.

DESCRIPTION

FIG. 1 is a perspective view of a computer chassis showing my new design;

FIG. 2 is a front elevational view thereof;

FIG. 3 is a rear elevational view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a partial enlarged view of FIG. 3;

FIG. 9 is a partial enlarged view of FIG. 6; and,

FIG. 10 is a partial enlarged view of FIG. 7.

The broken lines in the drawing depict environmental subject matter only and form no part of the claimed design.
